UNITED STATES PATENT OFFICE.

PAUL KLIMOWICZ, OF STEVENS POINT, WISCONSIN.

CHARACTER-MOUNTING STICK FOR CHANGEABLE SIGNS.

Application filed April 28, 1927. Serial No. 187,342.

The invention generally relates to display signs of the changeable type wherein the display characters are provided with projected prongs to engage a mounting board and secure said characters thereupon, and primarily has for its object to provide a simple character mounting stick to aid the mounting of the characters upon the board and to assure proper alignment and spaced relation of said characters when mounted.

In its more detailed nature the invention resides in the provision of a mounting stick having a hand hold at one end by which the stick may be manipulated, character prong receiving grooves in the stick and extending through one end and adapted to removably receive the character prongs and hold the characters in perfect alignment, indicia positioned relatively to said grooves to facilitate proper spacing of the characters, and an abutment edge or flange to engage the sign and guide the mounting of the characters in a proper line.

With the above and other objects in view that will hereinafter appear, the invention still further resides in the novel details of construction, combination and arrangement of parts, all of which will be first fully described, then be particularly pointed out in the appended claims, reference being had to the accompanying drawing, in which:—

Figure 1 is a face view of the characters aligning and applying stick, a series of characters being indicated in dotted lines.

Figure 2 is an edge view of the stick.

Figure 3 is a diagrammatic face view illustrating a series of sign characters, the mounting prongs being shown dotted and the alignment thereof being indicated by lightly drawn parallel lines.

Figure 4 is a view similar to Figure 3 showing a modified series of characters.

Figure 5 is an edge view of a dismounted character.

In the drawing, in Figures 3 and 4, I have illustrated a series of characters 6 of types of which changeable signs are commonly composed and it is to be understood that the characters may comprise letters, numerals, punctuation marks, and fancy designs of various sizes, shapes and styles such as are usually employed in the building up of changeable signs.

Each character 6 is provided with a pair of mounting prongs 7 projecting from the rear face thereof and the letters are usually con-

structed of cast metal or other suitable material such as will provide a neat appearance. As will be observed by reference to Figures 3, 4 and 5 of the drawings the prongs bear spaced relation in projection from the characters and also bear fixed relation with the upper and lower limits of the letters so that when the prongs are arranged in alignment as indicated by the light lines in Figures 65 3 and 4, such alignment of the prongs will assure the desired alignment of the characters as indicated in the said figures.

In building up a sign, or in other words, in applying the characters to form the display I employ a novel means for assuring the proper spacing of the characters and for greatly facilitating the assembly and application of the characters in their proper grouping and spaced relations.

This means which forms the subject matter of my present invention comprises an applicator stick 9 in the nature of a flat body formed of celluloid, aluminum, sheet steel, fibre, or any other suitable flat sheet material, and which includes a handle 10 at one end and a relatively long rectangular flat body portion. The flat body portion is provided with a pair of spaced parallel grooves 11 extending from a point adjacent the juncture of the handle with the body and through the opposite end of said stick. The uppermost face of the stick is also provided with suitable gradations or scale indicia indicated at 12 preferably formed along the upper edge defining the uppermost groove 11, and the said gradations may be made in the usual inch and eighth inch divisions of the usual linear measure, or of any other divisions found practical and desirable.

The body of the stick 9 at its juncture with the handle is also provided with down turned flanges 13 bearing cooperative relation with the grooves of the stick so that when the stick is laid against an edge of a sign board with the flanges flatly abutting that edge the desired position of the grooves relatively to the face of the sign board will be attained. This relation of the flanges with the grooves may, of course, be varied according to the particular use to which the stick is to be put.

In constructing a sign the letters or characters forming a line of the desired display are arranged on the stick in the manner indicated in dotted lines in Figure 1 of the drawings with their prongs 7 projecting through the grooves 11 in the stick. By thus

inserting the prongs in the grooves perfect alignment of the letters or characters is assured and by utilizing the scale 12 the desired spacing of the said characters may readily 5 and conveniently be obtained.

By now presenting the stick with the characters thereon to the face of a sign board in the desired position and with the flanges 13 against a convenient portion of the board, the 10 whole assembly of characters may be impressed upon the sign board by forcing the prongs thereof into said board. The stick may now be withdrawn by grasping the handle thereof and pulling the same toward the 15 left in Figure 1, the prongs readily slipping out through the open ends of the grooves 11. When the stick has been wholly removed the characters are forced home the remainder of the distance permitted by the length of their 20 prongs and that portion or line of the sign is complete. This operation being repeated, the whole sign is quickly and efficiently assembled and presents a neat and attractive appearance.

25 From the foregoing description, taken in connection with the accompanying drawings, it is thought that the novel details of construction, the manner of use and the advantages of my invention will be readily apparent to those skilled in the art to which it relates.

What I claim is:

1. A character aligning spacing and mounting stick comprising an elongated flat body 35 having a handle at one end and spaced par-

allel grooves extending through and along the body from adjacent the handle and through the opposite end, there being indicia on said stick body for the purpose specified.

2. In apparatus of the character described, 40 a character aligning spacing and mounting stick comprising an elongated flat body having a handle at one end and spaced parallel grooves extending through and along the body from adjacent the handle and through 45 the opposite end.

3. In apparatus of the character described, 50 a character aligning spacing and mounting stick comprising an elongated flat body having a handle at one end and spaced parallel 55 grooves extending through and along the body from adjacent the handle and through the opposite end, there being indicia on said stick body, and abutment flanges to engage a sign board edge and aid in positioning the characters being applied.

4. In apparatus of the character described, 60 a character aligning spacing and mounting stick comprising an elongated flat body having a handle at one end and spaced parallel 65 grooves extending through and along the body from adjacent the handle and through the opposite end, there being indicia on said stick body, and abutment flanges bent downwardly at right angles from the flat body adjacent the handle to bear transverse relation with said body at that end in a plane normal to the plane of said body.

PAUL KLIMOWICZ.
